FIG. 8.

OFFSET CHANGE APPARATUS FOR TRAFFIC CONTROL SYSTEMS

BACKGROUND OF THE INVENTION

1. Field of the Invention

The present invention relates to traffic control systems and particularly to apparatus for gradually, accurately and smoothly changing the offset at predetermined local traffic intersection controllers without disturbing the flow of vehicular traffic.

2. Description of the Prior Art

To fully appreciate the limitations of the prior art and to more readily understand the advantages of the present invention requires a brief description of the problem involved.

In many cities, efficient traffic flow can be obtained only through integrated control of a plurality of traffic signals located along a traffic artery. This permits employment of a progressive signaling system wherein successive signals along the artery are timed so that vehicles travelling at a predetermined velocity encounter a green signal indication at each successive intersection, after having once encountered a red signal indication along the artery. This requires that the local controllers for each of the succeeding signals be timed to initiate a local cycle after a predetermined interval from the time of initiation of the local cycle for the previously encountered signal. This interval, commonly known as local offset, may be obtained at each local controller by establishing a reference or background zero time and hence a reference or background cycle duration for the entire system and requiring the cycle timing means for each of the local controllers to be time-phased with respect to the system timing such that local zero time at any controller bears a predetermined phase relationship to system or background zero time, even though the same cycle duration, i.e., the background cycle duration, may be demarcated at each controller. This predetermined phase relationship is independently selected at each local controller, permitting any predetermined offset to be obtained at any such location.

The speed of traffic ordinarily varies with the amount of traffic congestion, generally being relatively high when congestion is low and decreasing substantially as congestion increases. This means that the offsets for the various controllers must be adjustable so that the particular offset values in effect at any time can readily be changed in accordance with traffic congestion.

The offset times for the several controllers must usually be made adjustable also in accordance with whether inbound or outbound traffic is to be favored at a given time. The offsets which must be established at the various intersections to provide the proper progression for one direction of traffic may be quite different from those which must be put into effect to effect a proper progression for traffic in the other direction. It is often necessary to favor one direction of traffic at one period of the day and to favor the opposite direction of traffic at other times since the relative traffic loads may shift quite appreciably between different periods. Quite commonly, it is desirable to select one set of offset values for the morning rush hour, a different set for the evening rush, and a third set for other times when it is best to favor both directions equally insofar as possible; these sets of values chosen in accordance with congestion. In any event, an integrated traffic signal control system should provide a means by which a particular one of a plurality of preset offset values can be selected at each individual controller location. For example, the system may be so organized that one set of offset values is selected for the several controllers in response to one kind of control signal received from the central office, and a second set of offset values in response to a second different signal.

Changing of the local offsets at the local controllers from one value to another when a new system offset has been established presents a design problem, since it is undesirable to instantaneously shift from the previous local offset value to the new local offset value. Instantaneous shift in local offset

may cause a significant portion of the local cycle to be skipped if the local cycle is required to start later in the background cycle, or may cause a portion of the local cycle to be repeated if the local cycle is required to start earlier in the background

cycle. To avoid this situation, any change in offset at a local controller must be accomplished gradually, over a period of possibly several background cycles if the change is drastic, so that no traffic phase is unduly lengthened or shortened. Hence, such change is accomplished by a temporary but slight increase or decrease in local cycle duration.

Certain prior art systems for making such offset changes employ electromechanical components which tend to be unreliable in that such components are subject to deterioration in performance due to environmental conditions and excessive usage.

Certain other prior art systems, when effectuating a change from a previous offset value to a newly commanded value, tend to overshoot the new value by a substantial amount and thus are required to reverse the direction of change to arrive at the new offset value. This procedure may disrupt the smooth flow of traffic.

Other offset changing systems employ an offset controlling element and a plurality of remotely selectable elements, each preset to a particular offset value. The offset controlling element is constrained to alignment with the selected element by means of a closed loop servomechanism arrangement. The effective offset at each controller is changed by changing the selection from the plurality of elements. The offset controlling element gradually realigns with the newly selected element thus accomplishing the required change. Under certain conditions, servomechanism configurations are prone to instability which can result in an oscillatory condition where the new offset value cannot be maintained in a stable condition.

Still other systems, when changing offset, effectuate large changes during the transitional cycles; thus confounding the efficient progression of traffic. Such systems often employ numerous and complicated computations throughout the offset change procedure.

As previously described, a reference zero time as well as a background cycle duration must be established for an integrated traffic control system. In the present apparatus, a sequence of uniform pulses is transmitted from the central office to a plurality of intersection controllers. One distinctive pulse is transmitted for every group of 199 uniform pulses. The distinctive pulse demarcates the reference zero time, and the background cycle duration is determined by the time interval between distinctive pulses. Thus every pulse represents one-half percent of the background cycle, the distinctive pulse representing 0 percent or the start of the background cycle. The 199th pulse following the distinctive pulse, thusly represents 99½ percent of the background cycle and the next occurring pulse, which is the distinctive pulse, represents 100 hundred percent of the background cycle as well as representing 0 percent of the next following background cycle.

If, for example, an offset change from 10 percent to 90 percent of background cycle is required, the transitional cycles can be slightly lengthened such that the transitional offset values will increase from 10 percent until the required 90 percent is achieved. Thus the intersection controller must undergo a change of 80 percent. If, however, the transitional cycles are shortened, the transitional offset values will decrease from 10 percent through 0 percent. Since 0 percent is equivalent to 100 percent, the values will further decrease until 90 percent is attained. Thus, in the latter instance, the total offset change is 20 percent. It is apparent that by proper selection between a shorter or longer transitional cycle, the total change need never exceed 50 percent of the background cycle.

The present invention contemplates subtracting the new offset value from the old offset value such that the algebraic difference is 50 percent or less by means of a reversible counter. In the previous example, the old offset value is 90 percent and the new offset value is 10 percent. Since subtract-

ing 10 percent from 90 percent yields 80 percent, one of the factors must be adjusted such that the difference will be 50 percent or less. Since 10 percent is equivalent to 110 percent, the subtraction of 110 percent from 90 percent yields an algebraic difference of -20 percent.

SUMMARY OF THE INVENTION

The present invention concerns apparatus for gradually changing the offset of a traffic intersection controller from an initial value to a new value by the most direct path and without overshoot. The algebraic difference between the previous and the new commanded offset value is obtained by use of a reversible counter. The apparatus also utilizes an offset controlling counter and a transitional cycle counter. The transitional cycle counter generates transitional cycle signals of 90 percent or 110 percent of the background cycle dependent upon the sign of the algebraic difference. The magnitude of the difference controls the termination of the change procedure. The apparatus of the present invention gradually and accurately changes the operating offset without requiring numerous and complicated numerical computations. Further, the offset change apparatus is utilized only during an offset change procedure when an offset change is actually commanded. The apparatus of the present invention does not require nor employ electromechanical components with their inherent difficulties explained above.

BRIEF DESCRIPTION OF THE DRAWINGS

FIG. 1 is a schematic diagram in block form of the offset change apparatus of the present invention;

FIG. 2 is a schematic wiring diagram of a portion of the control circuitry of FIG. 1;

FIG. 3 is a schematic wiring diagram of another portion of the control circuitry of FIG. 1;

FIG. 4 is a schematic wiring diagram of a portion of the forward-backward counter of FIG. 1;

FIG. 5 is a schematic wiring diagram of the sign generator of FIG. 1;

FIG. 6 is a schematic wiring diagram of the cycle counter of FIG. 1;

FIG. 7 is a schematic wiring diagram of the C5 generator of FIG. 1; and

FIGS. 8a and b are circular schematic drawings for explaining the offset change principle with respect to the apparatus of the present invention.

DESCRIPTION OF THE PREFERRED EMBODIMENT

A detailed explanation of the method and apparatus for generating offset command and other system signals is provided in U.S. Pat. application Ser. No. 453,072 entitled Traffic Intersection And Other Signal Controllers Responsive To A Cyclic Pulse Train of John J. King, filed May 4, 1965 now abandoned and assigned to the present assignee, as well as an explanation of certain terms and will not be repeated herein for the sake of brevity.

Referring now to FIG. 1, to provide an introductory synopsis the change offset operation is initiated by generating binary "ONE" signals on all four offset command lines A, B, C, D, which extend between a zone control station and a local traffic intersection controller which houses the apparatus to be described. The all "ONES" pattern is presented at approximately the halfway point in the background cycle to AND gate 10 shown in FIG. 1 and AND gate 11 of FIG. 2. The pattern lasts for a few cycle pulses, and then the binary signals representing the new offset command are presented on the offset command lines A, B, C, D. The all ONES pattern generates the offset change command and arms the control circuitry 12 in a manner to be more fully described. This maintains the previous or old offset signal in the offset storage re-

5 offset counter 18 which continues to generate the old offset overflow signal C5'. When the offset counter 18 overflows due to the all ONES pattern, the control circuitry 12 activates and reloads the old offset value into the offset counter 18. Then the ten's quantized value of this data is transferred via AND gate 20 to the forward-backward counter 21 until the offset counter 18 overflows. The counter 21 is a three-stage double ranked counter which counts from 0 to 5 in the forward direction, and back to 0 in the backward direction. An overflow signal is generated when the counter 21 goes beyond count 5 in the forward direction or when it goes beyond count 0 in the backward direction. This overflow signal automatically causes the counter 21 to change the direction of its count, i.e., from count forward to count backward and vice versa. The operation of the counter 21 is such that counting occurs at one clock time, sensing a counter overflow at a second clock time, storing the new count at a third clock time and changing counting direction at the fourth clock time. The 10 clock times are generated by conventional apparatus (not shown) within the local traffic intersection controller. After the offset counter 18 overflows, control circuitry 12 then gates the new offset command into the offset storage register 13 through offset decoder 15, offset switches 16 and encoder 17 to the offset counter 18. The control circuitry 12 then reverses the direction of the forward-backward counter 21 and transfers the ten's quantized value of the new data to the forward-backward counter 21. Thus, the new quantized data is subtracted from the contents of the counter 21 which represented 15 the old quantized data. The remaining count in the forward-backward counter 21 after this operation is the value of delta Δ and the counter direction is represented by the sign of delta Δ , i.e., + or - provided by the Δ sign generator 22. The control circuitry 12 then senses the contents of the counter 21 to 20 determine whether to start the cycle counter 23, or to wait for the next background cycle. The cycle counter 23 is a nine-stage binary counter, which can count 256 pulses. The counter 23 counts t percent pulses, where each pulse is a one-half percent of cycle assuming a background cycle of 200 pulses. The ninth stage of the counter 23 is the overflow stage. The 25 operation of the counter 23 is such that counting occurs at one clock time, overflow is sensed at a second clock time, reloading the counter at a third clock time and clearing the ninth stage at the fourth clock time. The counter 23 is preset to one of two values depending upon the sign of Δ . For $-\Delta$ sign, the counter 23 is preset to 36, which means the capability of counting 220 pulses or 110 percent of the background cycle. For $+\Delta$ sign, the counter 23 is preset to 76, which means the capability of counting 180 pulses or 90 percent of background cycle. The overflow of the cycle counter 23 is the C5'' signal. The overflow signal C5' of the offset counter 18 and the overflow signal C5'' of the cycle counter 23 are fed to the C5 generator 25. The C5 generator 25 determines which 30 of the two overflow signals shall generate the offset signal C5. The C5 signal is the operating offset signal for this background cycle in the local traffic intersection controller. The C5 generator 25 is responsive to control signals from the control circuitry 12 and the sign of Δ from the Δ sign generator 22 to 35 determine the choice of overflow signal C5' or C5''. An end of offset change signal is generated in the control circuitry 12 in the background cycle that the last offset change value occurs. This signal resets the armed offset change memory (not shown) which completes the offset change procedure in a 40 manner to be more fully described.

45 A detailed explanation of the present invention will now be provided by referring initially to FIG. 2. The offset change control circuitry 12 is armed by the all ONES pattern which enables AND gate 11. The AND gate 11 sets the change offset 50 C.O. flip-flop which prevents the offset storage register 13 from receiving the new offset command at the next background start signal. At the next background start signal, a

resets the N flip-flop through OR gate 31. The controller generates four clock times, i.e., w, x, y and z. Each clock time is 50 microseconds wide and there is a 50 microsecond dead time between two clock times. At the next x clock time, the AND gate 32 is enabled. The AND gate 32 generates the clear 0 signal. This signal resets the offset counter 18 to its initial condition, resets the percent count flip-flop (shown in FIG. 3) through OR gate 33, resets flip-flop 1 (shown in FIG. 3) through OR gate 34. At this time the offset counter 18 (shown in FIG. 1) is ready to accept data from the offset switches 16. At the next y clock time, the AND gate 36 (shown in FIG. 2) is enabled and generates s^{***} signal. This signal resets the forward-backward counter 21 to its initial state through OR gates 40, 41, 42 (shown in FIG. 4), sets the direction flip-flop (shown in FIG. 5) and sets the Δ start flip-flop (shown in FIG. 2). At 66 milliseconds after the leading edge of the start pulse, a guard time signal is generated. This signal is over 100 milliseconds wide. At the next y clock time, the AND gate 43 (FIG. 2) is enabled and generates the s^* signal. This signal sets the percent count flip-flop (FIG. 3) and generates the s^{**} signal through OR gate 44 (FIG. 2). The s^{**} signal loads the data from the selected offset switch of the switches 16 into the offset counter 18. Since the C.O. flip-flop is set, the old offset value is loaded into the offset counter 18.

At the next t percent pulse (z clock time), the AND gate 45 (FIG. 3) is enabled and its output is now used as the counting pulses by the offset counter 18. Thus the AND gate 45 presents z clock pulses to the offset counter 18 at the background cycle pulse rate until the offset counter 18 overflows in a manner similar to that described in said Ser. No. 453,072. At the time the offset counter 18 overflows, three pulses are generated. The first is the $C5'$ signal and occurs at w clock time. The second is the overflow x_o signal and occurs at x clock time. The third is the overflow y_o signal and occurs at y clock time. The OR gate 47 (FIG. 7) is enabled since the O.C. flip-flop is off thereby providing an O.C. signal to the OR gate 47. The $C5'$ signal therefore enables the AND gate 48 (FIG. 7) which enables the OR gate 49 and in turn enables the AND gate 50, since the N flip-flop is off thereby providing an N signal. The AND gate 50 generates the $C5$ pulse which at this time represents the overflow signal associated with the old offset value.

At this time the value of Δ and its sign are to be determined by the following procedure. At y clock time, the AND gate 51 (FIG. 2) is enabled through the overflow y_o signal and its output sets the N flip-flop and also generates via OR gate 44 the s^{**} signal which performs the operations discussed above. The AND gate 12 (FIG. 3) is enabled by the N signal from the N flip-flop to generate a train of z clock pulses. These pulses will be used to transfer the units overflow from the offset counter 18 to the forward-backward counter 21. The number of overflows of the units counter portion of the offset counter 18 represents the number of ten's in the data since the counter 18 is a decade counter. Thus, the offset data in the counter 18 can be quantized to ten's, by monitoring the units counter overflow. Then at the same time as AND gate 12 is enabled, the AND gate 52 (FIG. 4), which is included in the AND gate 20 (FIG. 1), is enabled to accept the units counter overflow.

The output of gate 52 enables OR gate 53 which generates the count Δ signal that is counted in the forward-backward counter 21. As shown in FIG. 4, the old offset data will now be counted into the forward-backward counter 21. The first count Δ pulse enables the AND gate 55, since the x_1 flip-flop is off and provides an $\bar{x}_2$ signal. The AND gate 55 sets the x_1 flip-flop and partially enables the AND gate 58. Since the counter 21 is in the forward direction, the AND gate 58 is disabled. At y clock time, the AND gate 60 sets the x_2 flip-flop to provide an x_2 signal. The second count Δ pulse enables the AND gate 56, since x_2 flip-flop is on. The AND gate 56 enables the AND gate 59 and the OR gate 40. The OR gate 40 output resets the x_1 flip-flop. The AND gate 59 enables OR gate 54 since the counter is in the forward direction. The OR gate 54 enables the AND gate 61 since the y_2 flip-flop is off.

and provides a $\bar{y}_2$ signal. At the next y clock time, the AND gate 62 resets the x_2 flip-flop and the AND gate 63 sets y_2 flip-flop. This operation continues until the z_2 flip-flop is set. If the data is generated through four pulses, the next count Δ pulse will again set the x_1 flip-flop through the AND gate 55. As shown in FIG. 5, at the next x clock time, the AND gate 66 sets the overflow flip-flop via OR gate 67. At the next y clock time, the AND gate 60 (FIG. 4) sets the x_2 flip-flop. At the next z clock time, the AND gate 68 (FIG. 5) is enabled, which enables OR gate 69. The OR gate 69 output toggles the direction flip-flop. Since the direction flip-flop was on before, the flip-flop is now toggled off, i.e., in the backward direction. If the data is greater than 5, the next count Δ pulse will enable the AND gate 56 (FIG. 4) which resets the x_1 flip-flop through the OR gate 40. At the same time, the overflow flip-flop (FIG. 5) is reset at w clock time through the OR gate 73. This operation will continue until all the data is transferred. Thus, the offset counter 18 will overflow providing a $C5'$ signal. At this time, the $C5'$ signal enables the AND gate 48 (FIG. 7) which in turn enables the OR gate 49. However, no $C5$ signal is generated for this offset counter overflow since the N flip-flop is on and the AND gate 50 is therefore disabled.

The new offset data is now loaded into the offset counter 18, and subtracted from the old offset data in the forward-backward counter 21. At the same w clock time, as the $C5'$ signal, the AND gate 80 (FIG. 2) is enabled and generates an L^* signal. This signal allows the new offset command to be inserted into the offset storage register 13 and resets the Δ start flip-flop through the OR gate 30. At the next y clock time, the overflow y_o signal enables the AND gate 81 which generates the L^{***} signal. The L^{***} signal sets the O.C. flip-flop, and loads the new offset data into the offset counter 18 through the s^{**} signal generated by OR gate 44. The L^{***} signal also enables the OR gate 69 (FIG. 5) which toggles the direction flip-flop thus changing the counting direction in the forward-backward counter 21. The L^{***} signal also resets the overflow flip-flop through the OR gate 73 (FIG. 5). This is to prevent a double toggle of the direction flip-flop in case of a counter overflow in the previous w clock time. The O.C. flip-flop (FIG. 2) is the change offset memory.

At the next z clock time, the new data is transferred to the forward-backward counter 21. Thus, the operation as described in the previous paragraph above is repeated. At the offset counter overflow caused by the transferring of the new offset value, the AND gate 82 (FIG. 2) is enabled and generates the D^{***} signal which gates the state of the direction flip-flop (FIG. 5) into the Δ sign flip-flop via AND gates 83 and 84. At the next x clock time, the AND gate 85 (FIG. 2) is enabled which generates the D^{**} signal. The D^{**} signal preloads the cycle counter 23 (FIG. 6) to the proper point through OR gate 86 and either AND gate 87 or 88. The D^{**} signal also sets the $V(w)$ flip-flop (FIG. 3). At the next y clock time, the AND gate 90 (FIG. 2) is enabled which generates the D^* signal. The D^* signal resets the N flip-flop through OR gate 31, resets the direction flip-flop (FIG. 5) and resets the overflow flip-flop through OR gate 73. The overflow flip-flop is reset in order to prevent a toggling of the direction flip-flop. At this time the value of Δ and the sign of Δ have been generated. The value of Δ is stored in the forward-backward counter 21 and the sign is in the Δ sign flip-flop (FIG. 5). Also, the forward-backward counter 21 has been aligned to reduce the value therein to zero.

Now the system determines if Δ is zero. A Δ value of 0 means that the difference in offset between the old and the new is less than 10 percent. If Δ is zero, the system will jump immediately to the new offset, otherwise it will proceed with the offset change operation. If Δ equals zero at D^* time, the contents of the forward-backward counter 21 is zero. Thus, AND gate 91 (FIG. 3) is enabled which enables AND gate 92. The AND gate 92 sets the C.E. flip-flop through OR gate 93, resets flip-flop 01 through OR gate 34 and resets flip-flop 02 through OR gate 35. The normal procedure in offset change operation is blocked by AND gate 94. The operation then

waits for the next background start at which time the new offset is loaded into and counted by the offset counter 18 and the operation described above with respect to the comparable background start is repeated. Since Δ is zero, the Δ sign flip-flop (FIG. 5) is in a $+\Delta$ state. Also, because Δ is zero, the auxiliary counter flip-flop (FIG. 6) is off. Thus OR gate 95 (FIG. 7) is enabled, which enables AND gate 96. The AND gate 96 in turn enables the OR gate 47. Thus, when the new offset C5' signal is generated, it will enable AND gate 48 which enables the OR gate 49 and thus the AND gate 50. The AND gate 50 generates the C5 signal. The C5 signal is the operating offset signal for this background cycle in the local traffic intersection controller. This signal enables the AND gate 97 (FIG. 3). The AND gate 97 generates the "end of offset change" signal, which resets the O.C. flip-flop (FIG. 2) thus resetting the offset change memory. At the next y clock time, the AND gate 98 (FIG. 3) resets the C.E. flip-flop. Thus the offset change circuitry is completely off. In the next background cycle, the new offset value is directly generated by the offset counter 18.

The operation of the ZERO OFFSET circuit will be described with respect to FIG. 3. For this condition, at D* time, the forward-backward counter 21 contains a count of one. The AND gate 92 is blocked and the AND gate 94 is enabled. The AND gate 94 generates the $V(w)w$ signal, which reduces the count in the forward-backward counter 21 by one through OR gate 53 (FIG. 4). The $V(w)w$ signal also sets the I.C. flip-flop. The AND gate 99 is enabled if the new offset value is greater than the old offset value, through AND gate 101 (FIG. 5). The output of this gate sets the flip-flop 1. At an x clock time later, the forward-backward counter 21 overflows, and enables AND gate 100 through AND gate 101 (FIG. 5). The AND gate 100 (FIG. 3) sets the C.E. flip-flop through OR gate 93. When the C.E. flip-flop is set, it indicates that the change offset operation will be completed in the next background cycle. At the same time the AND gate 102 resets the $V(w)$ flip-flop through the OR gate 103, sets the flip-flop 3 and sets the auxiliary counter flip-flop (FIG. 6). At the same time if the sign of Δ is negative, the AND gate 104 is enabled (FIG. 3). This gate generates the reset and clear offset counter signal which prevents the C5' signal from generating a C5 signal in the same background cycle as the C.E. flip-flop is turned on. At the same time AND gate 105 is enabled, which generates the CF signal. The CF signal sets the flip-flop 2 and resets the auxiliary counter flip-flop (FIG. 6) through OR gate 44. At the next w clock time, AND gate 106 (FIG. 3) resets the IC flip-flop and the last stage of the cycle generator 23 (FIG. 6). The circuitry now waits for the next background start.

The start pulse enables AND gate 108 (FIG. 3) which sets the S flip-flop, and resets the Δ start and N flip-flops. Thus, the new offset value is loaded and counted in the offset counter 18. The AND gate 108 generates the C5F signal which generates the C5 signal through OR gate 49 and AND gate 50 (FIG. 7). The C5 signal is the operating offset signal, for this background cycle in the local traffic intersection controller. Thus the offset counter 18 is counting, and a zero offset is generated. The C5 signal enables AND gate 97 which generates the end of offset change signal. This signal clears the OC and CE flip-flops in a manner explained above. As shown in FIG. 7, when the offset counter 18 overflows, the C5' signal generates the C5 signal through the OR gate 47, AND gate 48, OR gate 49 and AND gate 50. Thus, during the same background cycle, two operating offset signals are generated.

When the difference in offset is greater than 10 percent, the AND gate 91 (FIG. 3) is disabled since the forward-backward counter 21 contains a count greater than zero. Thus the AND gate 92 is disabled. Then the operation as described in the two preceding paragraphs is repeated if the counter contains a binary 1. The cycle counter 23 now counts t percent pulses through AND gate 110 (FIG. 6). The counting will usually overlap the next background start. At the next background start, the start pulse is again generated. Thus again loading and

counting the new offset value as explained above. When the cycle counter 23 overflows at w clock time, the AND gate 111 (FIG. 6) generates the C5'' signal. The C5'' signal resets the auxiliary count flip-flop through the OR gate 44. For the conditions of $+\Delta$ sign operation, the C5 signal is chosen from the counter overflow occurring last (C5' or C5''). The C5'' signal is chosen as shown in FIG. 7 through OR gate 112, AND gate 113, OR gate 49 and AND gate 50. The C5' signal is chosen through OR gate 95, AND gate 96, OR gate 47, AND gate 48, OR gate 49 and AND gate 50. For the condition of $-\Delta$ sign operation, the C5 signal is chosen from the counter overflow occurring first (C5' or C5''). The gating is the same as previously explained. At the next x clock time, as shown in FIG. 6, the cycle counter 23 is preloaded through OR gate 86 and either AND gate 87 or 88. The C5 signal generates the end of offset change signal through AND gate 97 (FIG. 3). This signal clears the OC flip-flop (FIG. 2) and CE flip-flop (FIG. 3). At the next z clock time, the AND gate 115 (FIG. 6) resets the cycle counter overflow stage. Thus the offset change circuitry is reset. If the counter contains a count greater than 1, the steps are repeated with the C5'' signal again generating the $V(w)w$ signal through OR gate 116 and AND gate 94 (FIG. 3). The operation is continued until the count in the forward-backward counter 21 is reduced to 1 and ultimately until the offset change circuitry is reset as explained above.

As explained above, once the value and sign of Δ are determined, an internal cycle clock is started. The internal clock counts up to either 90 percent of the background cycle (for $+\Delta$) or 110 percent (for $-\Delta$). The internal cycle clock is started at the point when the offset counter 18 containing the old offset value overflows. The term "old offset" refers to the operating offset before the offset change procedure explained above. Conversely, the new offset refers to the operating offset after an offset change procedure. When the cycle clock overflows providing a C5'' signal, it is used as the first offset change point C5 for that background cycle. The value of Δ is then reduced by one, and the cycle clock is reset and is started counting again. This operation continues until the value of Δ is zero. At each background cycle during the offset change operation, the offset counter 18 generates the new offset value C5'. At the background cycle that Δ equals zero, the change offset point C5 is chosen from either the cycle clock overflow signal or the offset counter overflow signal. The choice is a function of the direction in which the offset change is being made, i.e., the sign of Δ . The concept of two clocks simultaneously running and choosing one overflow (at $\Delta=0$), removes any anomalies that might otherwise exist. Further, the offset changes are true 10 percent incremental changes, not 10 percent of the quantized values.

As an example of this method will be described referring to FIG. 8. Assume that an offset change from 22 percent to 67 percent is required as shown in FIG. 8a. The operation would be to calculate the magnitude of Δ [$\Delta=4$] the sign of Δ (sign $=-\Delta$). At old offset point, i.e., 22 percent in the background cycle, the internal cycle clock is set to count 110 percent, starts counting and the value of Δ is decreased to 3. In the next background cycle, the cycle clock overflows at 32 percent. Thus, the first offset change value is 32 percent. Δ is decreased to 2, and the cycle clock resets to 110 percent and starts counting again. In the second background cycle, the offset change value is 42 percent. In the third background cycle, the offset change value is 52 percent and Δ is decreased to 0. In the fourth background cycle, the circuitry would choose as the offset value the overflow, i.e., C5' or C5'' whichever occurs first. In other words, at this background cycle the amount of offset change needed to obtain the new offset value is 15 percent (67 percent-52 percent). Thus by choosing the cycle clock overflow, the system stays within the 10 percent step requirement. Then in the fourth background cycle, the offset change value is 62 percent. In the next background cycle, the circuitry generates the new offset value (67 percent).

As a second example, as shown in FIG. 8b, assume an offset change in the opposite direction from 62 percent to 27 per-

cent. The value of Δ is again 4, but the sign is $+\Delta$. At the old offset point (62 percent), the cycle clock is set to count 90 percent of background cycle. The value of Δ is decreased to 3, and the counter starts counting. In the first background cycle, the offset change value is 52 percent and Δ decreased to 2. In the second background cycle, the offset change value is 42 percent and Δ decreased to 1. In the third background cycle, the offset change value is 32 percent and Δ decreased to 0. In the fourth background cycle, the system selects as the offset value the overflow $C5'$ or $C5''$ which occurs last. At this background cycle, the amount of offset change needed to obtain the new offset value is 5 percent. Thus by choosing the offset counter overflow $C5'$, the system will pass over the cycle clock overflow value. Then, the offset value for this background cycle is 27 percent. For a certain condition of changing offset through the value of 0 percent, the Zero offset circuit is activated. The gate description of this circuit was discussed previously. This condition exists for changes in offset of less than 10 percent, where the old offset is less than 10 percent and the new offset is greater than 90 percent. For this condition the value of Δ equals 1, and sign is $+\Delta$. When Δ is decreased to 0, the circuitry will attempt to choose between the two overflows. Since Δ is decreased to 0 in the same background cycle as the operation began, the offset counter will not begin counting the new offset until the next background cycle. Thus, in the initial background cycle, only the cycle clock overflow $C5''$ will be generated. Hence, the circuitry chooses the cycle clock overflow. For a change offset of 2 percent to 98 percent, the first background cycle would give the offset values, 2 percent and 92 percent. Thus, passing over the new offset value. This operation is modified by the zero offset circuit. The circuit stops the counting of the cycle clock, and generates a zero offset signal $C5$ in the next background cycle. Thus in the first background cycle it would have two offset values, i.e., 0 percent offset and the new offset.

While the invention has been described in its preferred embodiment, it is to be understood that the words which have been used are words of description rather than limitation and that changes within the purview of the appended claims may be made without departing from the true scope and spirit of the invention in its broader aspects.

We claim:

1. In apparatus for gradually changing the offset of a traffic intersection controller synchronized by means of a background cycle from a first offset value to a second offset value upon initiation of a command signal comprising,
  - a. control means adapted to be enabled by said command signal to change the offset value from said first to said second value;
  - b. offset timing means sequentially responsive to signals representative of said first and second offset values for generating first and second offset signals respectively in accordance with first and second offset cycles;
  - c. computing means coupled to said control means and said offset timing means for obtaining the algebraic difference between said first and second offset values when said control means is enabled such that said algebraic difference represents an offset change not in excess of fifty percent of said background cycle;
  - d. cycle timing means responsive to said control means and said computing means for generating successive transitional offset signals when said control means is enabled for initiating successive transitional offset cycles selectively shorter or longer than said background cycle in accordance with the sign of said algebraic difference; and
  - e. selection means responsive to said offset timing means and said cycle timing means for selecting between said second offset signal and said transitional offset signal for initiating the operational cycles of said controller such that said operational cycles change gradually towards said second offset cycle.
2. In apparatus of the character recited in claim 1 and further including:

diminishing means coupled to said computing means for gradually diminishing the absolute value of said algebraic difference; and terminational means responsive to the zero value of said algebraic difference for disabling said control means.

5 3. In apparatus of the character recited in claim 1 wherein said offset timing means includes a two-stage decimal counter having a units order stage and a tens order stage where said second offset signal is derived from an overflow signal from said tens order stage.

10 4. In apparatus of the character recited in claim 1 wherein said computing means comprises:

15 forward-backward counter means having a full count representing 50 percent of said background cycle and adapted to count forward upon attaining the count of zero and adapted to count backward upon attaining said full count;

means for sequentially counting said first offset value and said second offset value into said counter means; means for reversing the direction of count between said counting of said first and second offset values; and means for storing said direction of count after counting said second offset value.

20 5. In apparatus of the character recited in claim 4 wherein said cycle timing means comprises additional counter means adapted to count a transitional cycle time duration selectively shorter or longer than said background cycle, said selection being dependent on said stored direction of count.

25 6. In apparatus of the character recited in claim 5 wherein said shorter time duration is selected if said stored direction of count is backward and wherein said longer time duration is selected if said stored direction of count is forward.

30 7. In apparatus of the character recited in claim 5 wherein said shorter time duration is 90 percent of said background cycle duration and wherein said longer time duration is 110 percent of said background cycle duration.

35 8. In apparatus of the character recited in claim 2 wherein said diminishing means diminishes the absolute value of said algebraic difference during each transitional cycle by an amount representing 10 percent of said background cycle duration until said absolute value is reduced to zero.

40 9. In apparatus of the character recited in claim 1 and further including quantizing means responsive to said enabled control means for numerically rounding said first and second offset values to the nearest higher power of 10 and for dividing said rounded values by 10, and wherein said computing means responsive to said enabled control means algebraically subtracts said quantized second offset value from said quantized first offset value such that the algebraic difference in absolute value is not in excess of 5.

45 10. In apparatus of the character recited in claim 9 wherein said quantizing means and said offset timing means include a two-stage decimal counter having a units order stage and a tens order stage wherein said quantized offset values are derived from the overflow signal from said units order stage and said second offset signal is derived from the overflow signal from said tens order stage.

50 11. In apparatus of the character recited in claim 9 wherein said computing means comprises:

a modulo six forward-backward counter adapted to count forward upon attaining the count of zero and adapted to count backward upon obtaining the count of five;

means for sequentially counting said quantized first offset value and said quantized second offset value into said counter;

means for reversing the direction of count between said counting of said quantized first and second offset values; and

means for storing said direction of count after counting said quantized second offset value.

55 12. In apparatus of the character recited in claim 11 wherein said cycle timing means comprises still another counter adapted to count a transitional cycle time duration

selectively shorter or longer than said background cycle, said selection being dependent on said stored direction of count.

13. In apparatus of the character recited in claim 12 wherein said short time duration is selected if said stored direction of count is backward and wherein said long time duration is selected if said stored direction of count is forward.

14. In apparatus of the character recited in claim 13 wherein said short time duration is 90 percent of said

background cycle duration and wherein said long time duration is 110 percent of said background cycle duration.

15. In apparatus of the character recited in claim 9 wherein said diminishing means diminishes the absolute value of said algebraic difference by unity each transitional cycle until said absolute value is reduced to zero.
